UNITED STATES PATENT OFFICE.

WILLIAM W. BLAKELY, OF DETROIT, MICHIGAN.

WHEEL BLOCK.

Application filed May 21, 1928. Serial No. 279,525.

This invention relates generally to wheel blocks, particularly those designed for holding vehicles against movement within carriers while in transit and consists in certain 5 novel features of construction, combinations and arrangements of parts as will be more fully described and pointed out in the appended claims.

- In the accompanying drawings:
10 Figure 1 is a side elevation of a wheel block embodying my invention;
Figure 2 is a rear end elevation thereof;
Figure 3 is a detailed perspective view of a portion of the device; and
15 Figure 4 is a modified form of the invention.

Referring now to the drawings, 1 is a wheel engaging member, and 2 and 2' respectively are braces therefor of a wheel 20 block embodying my invention. As shown, the member 1 is constructed of relatively heavy gage sheet metal and is similar to the wheel engaging section designated by the numeral 2, in United States Patent No. 25 1,621,504 dated March 22, 1927 except that in the present instance the brace engaging or bearing portion consists of a flat depending flange 3 projecting from the upper edge of the member 1. Secured to this flange is an 30 elongated plate 4 provided at spaced points intermediate its ends with lateral outwardly projecting channel portions 5 which cooperate with the plate 3 to form tubular sockets 6. Preferably the plate 4 is riveted or welded 35 to the flange 3 so as to form in substance an integral part of the member 1.

In the present instance, the braces constitute metallic rods that are tubular in form. As shown, these rods are provided 40 at their lower ends with flattened foot or attaching portions 7 for engagement with the flooring of the carrier and are provided at their upper ends with socket engaging portions 8 that are adapted to be received 45 in the sockets 6 on the wheel engaging member. Preferably the sockets 6 and engaging portions 8 of the rods are substantially 50 square-shape in cross section and have snug engagement so as to prevent any turning 55 of the braces relative to the wheel block engaging member 1, when the parts are assembled.

With this arrangement the wheel block may be easily and quickly assembled by inserting the portions 8 of the brace rods in the sockets 6 and then nailing the member 1

and the flattened foot portions 7 to the flooring of the carrier.

Referring to Figure 2, it will be noted that the portion 8 of each brace is set at an 60 angle to the intermediate tubular portion thereof, the arrangement being such that when assembled the braces will diverge downwardly and outwardly from each other. This will space the flattened foot portions 65 7 a greater distance from each other than if the portions 8 were in vertical alignment with the tubular portions and thereby permit the braces to withstand greater stresses and strains than otherwise. 70

From the foregoing, it will be apparent that when the parts are in assembled relation and in use, the weight of the vehicle wheel will be amply sufficient to effect a firm engagement of the portions 8 of the braces 75 in the sockets 6. Thus a very simple and inexpensive but exceedingly strong, durable, and efficient construction is provided.

In Figure 4, a modified form of the invention is shown in which sockets for receiving 80 the braces are formed integrally with the wheel block engaging member. In this construction, the upper end of the wheel block engaging member is provided with a flattened portion 9 terminating in an open return bent portion 10 positioned directly beneath the same. Each of the portions 9 and 10 are provided with struck out portions 11 and 12 respectively, the portions 12 being positioned directly in alignment with the 85 portions 11 and forming therewith tubular sockets adapted to receive braces 13 in a manner similar to that described above.

While it is believed that from the foregoing description, the nature and advantage 90 of my invention will be readily apparent, I desire to have it understood that I do not limit myself to the specific construction herein shown and described and that such changes may be resorted to when desired as 95 fall within the scope of what is claimed.

What I claim as my invention is:

1. In a wheel block, an inclined wheel engaging member, a plate secured to said member at the upper end thereof and forming therewith a pair of laterally spaced sockets, and braces for said wheel engaging member having portions received in said sockets. 105

2. In a wheel block, an inclined wheel engaging member, a plate secured to said member at the upper end thereof and forming therewith a pair of laterally spaced sockets, 110

and rods constituting braces for said wheel engaging member having portions detachably received in said sockets.

3. In a wheel block, an inclined wheel engaging member having a depending flange at the upper end thereof, a plate secured to said flange and forming therewith spaced sockets, and braces for said wheel engaging member having end portions received in said 10 sockets.

4. In a wheel block, an inclined wheel engaging member having a depending flange at one end thereof, a plate secured to said flange and forming therewith spaced sockets, 15 and braces for said wheel engaging member comprising tubular rods having socket engaging portions projecting therefrom and receivable in said sockets, said socket engaging portions lying in planes inclined to the planes of said rods whereby said braces 20 will diverge downwardly and outwardly from each other when in assembled position.

5. In a wheel block, an inclined wheel engaging member having a depending flange 25 at one end thereof, a brace for said wheel engaging member formed separately from said member, and a connection between said brace and member including a plate secured to said depending flange and forming there- 30 with a socket for receiving a portion of said brace.

6. In a wheel block, an inclined wheel engaging member having a depending flange at one end thereof, a brace for said wheel 35 engaging member formed separately from

said member, and a connection between said brace and member including a plate secured to said depending flange and having a lateral outwardly projecting channel portion co-operating with said flange to form a socket 40 for receiving a portion of said brace.

7. In a wheel block, an inclined wheel engaging member, and a brace therefor comprising an intermediate tubular portion, a flattened floor engaging portion extending 45 from one end of said tubular portion, and a part projecting from the other end of said tubular portion and detachably engageable with said wheel engaging member.

8. In a wheel block, an inclined wheel 50 engaging member provided at one end with a socket, and a brace for said member comprising an intermediate tubular portion, a flattened floor engaging portion extending from one end thereof, and a portion projecting from the other end of said tubular portion and receivable in said socket.

9. In a wheel block, an inclined wheel engaging member provided with laterally spaced sockets, and braces for said wheel 60 engaging member having portions received in said sockets.

10. In a wheel block, an inclined wheel engaging member provided at its upper end with a pair of laterally spaced sockets, and 65 braces for said wheel engaging member having portions received in said sockets.

In testimony whereof I affix my signature.

WILLIAM W. BLAKELY.
